UNITED STATES PATENT OFFICE.

PERRY T. DENMEAD, OF AKRON, OHIO, ASSIGNOR TO THOMAS W. ROSS, OF CLEVELAND, OHIO.

MATCH-STICK.

1,054,680.

Specification of Letters Patent.

Patented Mar. 4, 1913.

Application filed February 4, 1910. Serial No. 542,113.

To all whom it may concern:

Be it known that I, PERRY T. DENMEAD, a citizen of the United States, residing at Akron, in the county of Summit and State 5 of Ohio, have invented new and useful Improvements in Match-Sticks, of which the following is a specification.

This invention relates to match-sticks and the object thereof is to provide a match- 10 stick which will burn more readily than the common match-stick of commerce and which can be more readily and thoroughly impregnated with the paraffin used for assisting combustion of the sticks and ordi- 15 narily extending rearwardly from the head of the match.

This invention while fully capable of being employed in connection with match- 20 sticks formed of soft wood, is more particu- larly designed for use in connection with match-sticks formed from hard wood, the use of which has heretofore been commer- 25 cially impracticable, by reason of the fact that they are not readily ignited by the flame generated by the head even with the assistance of a coating of paraffin extending rearwardly therefrom, and hence the use of hard wood has not been attended with satisfactory results.

30 In view of the fact that the forests of pine and other soft wood are being rapidly depleted, recourse must now be had to hard wood to furnish the supply of match-sticks required, but as already stated, they do not 35 ignite readily from the head and when ignited do not continue to burn so as to make the same a practicable and useful article.

I have discovered that by scarifying the 40 body of the stick, preferably by scoring, grooving or incising the same longitudinally of the stick and sufficiently deeply to permit the melted paraffin into which the match-stick is dipped to enter the fiber of the wood and to a certain extent impregnate 45 the same, it assists perfect combustion of the stick and at the same time the scoring of the surface of the stick to a more or less extent exposes the fiber of the wood to the oxygen of the air, thereby serving to assist 50 complete combustion of the match-stick.

My invention further contemplates im- 55 pregnating only a portion of the match- stick with paraffin, so that when the flame has reached the point where the paraffin im- pregnation ceases, the burning of the match-

stick ceases, thereby preventing the match- stick burning down to the fingers.

With the foregoing and other objects in view, the invention consists in the novel construction, combination and arrangement 60 of parts constituting the invention, to be hereinafter specifically described and illustrated in the accompanying drawings which form a part hereof wherein is shown the preferred embodiment of the invention, but 65 it is to be understood that changes, variations and modifications can be resorted to which come within the scope of the claim hereunto appended.

In the drawings, in which similar refer- 70 ence numerals indicate like parts in the different figures: Figure 1 is a perspective view, greatly enlarged, of a type of match- stick showing the scarifications thereon. Fig. 2 is a view similar to Fig. 1 of a com- 75 plete match; and, Fig. 3 is a view in trans- verse section on line X of Fig. 2.

Referring to the drawings in detail, the reference numeral 1 denotes a wooden match-stick preferably having two wide 80 faces and two comparatively narrow sides, although the material of which it is composed and its dimensions are all a matter of taste or selection and may be altered or changed without in any manner departing 85 from the scope of this invention. The two wide faces of the match-stick are generally preferably provided with scorings 2 which may be produced by any suitable tool and in any preferred manner and of any length 90 which experience has shown to be best for the purpose and for the material employed.

The scorings 2 should be sufficiently deep 95 to open up and expose a considerable portion of the fiber of the match-stick on the faces so treated and are preferably arranged closely together in order to cover as much of the surface thereof as possible, the nature of the scorings being governed largely by the material employed and the size and thickness of the match. After being scored, the sticks are preferably partially immersed in a bath of melted paraffin or coating 3 which adheres to the end of the match, and I prefer- 100 ably terminate this coating at the point 4, which may be easily accomplished by limit- 105 ing the amount of immersion or dip given to the match-sticks in the paraffin, to the end that when the portion covered or coated by the paraffin is consumed, the match will 110

cease burning for want of proper material on which to feed. The paraffin is usually applied in a melted condition and extremely hot and in this condition is very thin which causes it to absorb or sink into the material of the wood and to a certain extent impregnate the outer surface of the stick, causing the coating to more firmly adhere to the same and also causing more intense and perfect combustion.

10 The last operation consists in dipping the paraffin covered end of the match-stick in a suitable composition to produce an ignitable head 5 in the ordinary manner well known in the art.

15 A match produced by the foregoing method is sufficiently strong and rigid to be readily ignited by frictional engagement with any ordinary surface and after ignition the flame of the head is communicated to the paraffin impregnated wood whose fiber is roughened and opened by the scorings on the surface thereof which causes it to be readily combustible and will under 20 ordinary circumstances burn to the point 4 where the coating or impregnation of the paraffin terminates.

I am aware that heretofore, and before 25 my invention, matches have been made in which the body-portion of the match has an irregular exterior surface. Such match

bodies, however, are due to the particular arrangement of the cutting knives which are so disposed that the cutting eye of one knife overlaps the cut made by the eye of an adjacent knife, the knives being disposed in this manner to effect a saving of the wood used. This results in a groove or grooves being produced throughout the length of the match body, but it is to be noted that such match bodies have the exterior face all of the same nature, that is, comparatively smooth and compressed by the knife, or in other words, the exterior face of the match body is the same at all points throughout, there 30 having been no opening up or roughening of the surface subsequent to the passage of the knife thereover, by scoring the same in order to render the wood more combustible.

I claim:

A match having a hardwood splint provided on substantially its entire surface with superficial longitudinal incisions such as to displace the fiber of the wood without removal of the material.

55 In testimony whereof I have hereunto set my hand in presence of two subscribing witnesses.

PERRY T. DENMEAD.
